UNITED STATES PATENT OFFICE

168,626

STOCKING

William M. Langer, Berlin, N. J.

Application March 25, 1952, Serial No. 19,041

Term of patent 7 years

(Cl. D47—7)

To all whom it may concern:

Be it known that I, William M. Langer, a citizen of the United States, residing at Berlin, in the county of Camden and State of New Jersey, have invented a new, original, and ornamental Design for a Stocking, of which the following is a specification, reference being had to the accompanying drawing, forming a part thereof.

In the drawing, Fig. 1 is a side elevational view of a stocking embodying my new design; Fig. 2 is an enlarged, fragmentary, rear elevational view of a stocking embodying my new design; and Fig. 3 is an enlarged fragmentary side elevational view embodying my new design.

The essential feature of my design comprises a pair of lines along the splicing and connected with one another by cross bars, the cross bars being spaced from one another by a substantially

greater distance than the space between the lines which they connect, and the lines and bars contrasting in appearance with both the splicing and the body of the stocking as shown.

I claim:

The ornamental design for a stocking, as shown and described.

WILLIAM M. LANGER.
